UNITED STATES PATENT OFFICE.

DANIEL BRODERICK, OF NEW YORK, N. Y.

DESIGN FOR A COMBINED ASH-RECEIVER, CIGAR-REST, AND MATCH-BOX HOLDER.

50,605.

Specification for Design.

Patented Apr. 17, 1917.

Application filed February 5, 1917. Serial No. 146,854. Term of patent 7 years.

To all whom it may concern:

Be it known that I, DANIEL BRODERICK, a citizen of the United States, and resident of the borough of Queens, in the city and State of New York, have invented a new, original, and ornamental Design for a Combined Ash-Receiver, Cigar-Rest, and Match-Box Holder, of which the following is a specification, reference being had to the accompanying drawing, forming part thereof.

My new design for a combined ash receiver, cigar rest and match-box holder is shown in perspective in the accompanying drawing.

I claim:

The ornamental design for a combined ash receiver, cigar rest and match-box holder, as shown.

DANIEL BRODERICK.
